UNITED STATES PATENT OFFICE.

REGINALD J. MORTON, OF SPRINGFIELD, MASSACHUSETTS.

DIMMER DEVICE FOR AUTOMOBILE-HEADLIGHTS.

1,218,104.

Specification of Letters Patent.

Patented Mar. 6, 1917.

Application filed February 25, 1916. Serial No. 80,408.

To all whom it may concern:

Be it known that I, REGINALD J. MORTON, a citizen of the United States of America, residing in the city of Springfield, county 5 of Hampden, and State of Massachusetts, have invented certain new and useful Improvements in Dimmer Devices for Automobile-Headlights, of which the following is a specification.

10 This invention relates to improvements in dimmer devices for headlights, particularly for those used on an automobile for preventing the glare of an approaching machine which would cause the driver to be blinded 15 so that he could not properly see the roadway ahead of him. On account of the dazzling effect of undimmed headlights on automobiles serious accidents have often resulted.

20 The present invention, broadly considered, comprises an insertible piece of elastic and flexible material, preferably of celluloid or fiberoid, which is of a translucent nature and of a dark green color, in order to permit only green rays of light to pass therethrough. This piece is designed to be readily clamped in place by engaging the neck portion of an electric lamp and the inner lower part of a reflector. The device 25 also has attached thereto a shield made of the same material, the upper portion of which is rendered opaque, whereby the direct rays from the lamp are shielded or prevented from blinding the driver of the approaching machine.

Referring to the drawings:

Figure 1 is a vertical sectional view through the reflector, showing the insertible piece in place, and the shield located in front 40 of the lamp and attached to the insertible piece;

Fig. 2 is a detail plan view of the shield clearly illustrating the integral wings for attaching the same to the insertible piece 45 and the curved formation of this shield whereby the rays of light are prevented from escaping past the edge of the same.

Fig. 3 is a plan view of the insertible piece and showing the shield attached thereto; 50 and

Fig. 4 is a front elevational view of the lamp illustrating the insertible piece in place, together with the shield attached to this piece.

55 Referring to the drawings in detail: 1 designates the metal reflector element of the

headlight usually of a parabolic formation with its inner surface polished or silvered; 2 the electric lamp shown in dotted lines and 3 is the sector shaped insertible member that is designed to be placed within the reflector 1 and on the lower portion thereof as clearly shown in Fig. 1. This sector shaped piece is formed with an opening 4 and a slit 5, the slit 5 permitting the opening 4 to receive the neck of the lamp 2, as shown. The extent of the arc of the sector shaped portion is such that its upper edge 6 extends nearly one half of the distance from the bottom toward the top of the reflector, 70 as shown in Fig. 1. It will be noticed that the position of the member 3 when in place does not follow the same curvature of the reflector but is spaced therefrom as shown in Fig. 1 so that the rays of light indicated 75 by the broken lines 7 will be directed outward from the reflector at such an angle that they will, in turn, take substantially the path indicated at 8. That is to say, they are bent substantially upward as shown ahead of the 80 machine and not in a parallel direction as in an ordinary reflector or headlight. The rays of light emitted from the filament of the lamp that engage the upper inner surface of the reflector will of course follow the same 85 path as before the insertion of the member 3. They will of course be modified in color by this member so as to subdue the glare. The rays of light emitted from the filament of the lamp that are directed downward 90 against the member 3 will be thrown forward from the curved surface of the member 3 but not in the same direction as if the piece 3 was not inserted. It is to be understood that the reflected rays from the insertible 95 piece do not necessarily follow the lines shown. They are merely illustrative.

In order to effectually cut off the direct rays of light from the lamp 2 a shield 9, preferably curved, as shown, is employed. 100 This shield is preferably made of the same material as the insertible member 3, the upper portion of which is rendered opaque, as indicated at 10, by scratching the surface with sand paper or emery cloth. The shield 105 9 is removably attached to the insertible piece 3 by means of the integral wings 11, which are angularly disposed to the piece 9. These wings are slipped through the inclined shaped openings 12 for holding the shield in 110 place. It will be noticed that the shield 9 is curved as shown in Fig. 2 in plan view,

so that the rays of light that are emitted from the lamp 2 will be prevented from escaping past the edges 13 and engaging the silvered surface of the reflector 1 but are directed backward so as to strike the insertible member 3, where they are, in turn, reflected from the green surface of the member 3. The effect of the insertion of this piece of celluloid or fiberoid of dark green is that the person approaching the headlight sees only the subdued green light while the rays that are thrown forward onto the ground are strong white rays of sufficient brightness to permit the driver to plainly see the roadway, and at the same time prevent the glare or dazzle of the headlight to the driver of an approaching machine in the opposite direction.

I do not limit myself to the use of celluloid or fiberoid as any suitable substance may be used that will accomplish the purpose of the invention. The insertion of the opaque flexible material as herein shown and described causes, in practice, the diffused light near the forward end of the vehicle, whereby the outlines of the machine may be seen by a driver of an approaching machine, and also the headlight throws a beam of light forward similar to the concentrated rays of a searchlight. These rays engage the roadway a considerable distance ahead of the machine and are directed downward and not in a parallel direction, whereby the driver of an approaching machine only sees the subdued or diffused rays adjacent the machine and the driver of a machine is able to see the roadway ahead of him on account of the condensed rays of light that are thrown forward in a downward direction.

It should be stated that the position of the lamp in the reflector of course determines the direction of the reflector rays, that is to say whether they are projected in either an upward or downward direction. In the position of the lamp, as shown, the reflected rays from the insertible piece 3 will be upward, and the reflected rays from the upper inner surface from the reflector will be downward onto the road bed.

What I claim is:

1. An attachment for headlights for the purpose of reducing the glare, and comprising an arc-shaped piece formed of elastic material of a translucent nature and dark color that is adapted to be inserted in the lower portion of the reflector of a headlight, the apex portion of the sector-shaped piece having an opening to receive the shank of the electric bulb and a slit communicating with the opening to permit the insertion of the member within the reflector of the head-

light, and a shield secured to the sector shaped member for cutting off the direct rays of light from the lamp, as described. 65

2. A headlight dimmer, comprising an elastic member formed of material of a translucent nature and dark color and adapted to be easily bent and inserted into the reflector of a headlight, means for attaching the same to the lamp, and a curved shield connected to said member and extending upward and in front of the lamp when the dimmer is in place, whereby the direct rays of light are confined to the interior of the reflector, as described. 75

3. A device for subduing the glare or dazzling effect of an automobile headlight, comprising an insertible and foldable member adapted to be placed in the lower portion of the reflector of the headlight, and a shield attached to the member for cutting off the direct rays of light from the lamp. 80

4. A device for subduing the glare or dazzling effect of an automobile headlight, comprising an insertible member adapted to be placed in the lower portion of the reflector of the headlight and provided with slits, and a shield for cutting off the direct rays of light from the lamp, said shield being 90 provided with means for engaging the slits in the insertible member. 85

5. A member composed of an elastic material for insertion in the reflector of an automobile headlight, said member having 95 an opening to receive the neck of the electric lamp, and slits or openings for securing the shield thereto, and a shield which is located in front of the lamp to cut off the direct rays from the lamp, the upper 100 portion of said shield being rendered opaque and said shield being secured to said member by means of the slits. 100

6. A device for reducing the glare or dazzling effect of an automobile headlight, comprising a sector shaped piece of translucent material located in the lower portion of the reflector, and bent to conform substantially to the lower surface of the reflector from the front to the forward portion of the reflector, and means mounted on said device separable from the sector shaped piece for shielding the direct rays of light from the lamp of the headlight. 105

7. A sector-shaped piece for insertion 115 within and adjacent the lower part of the reflector of a headlight, means for attaching the same to the neck of an electric lamp, and means secured to said piece having an opaque surface for cutting off the direct 120 rays from the lamp.

REGINALD J. MORTON.
